UNITED STATES PATENT OFFICE.

THOMAS BULMAN, OF OSYOOS, BRITISH COLUMBIA, CANADA.

CARTON.

Application filed May 6, 1925, Serial No. 28,469, and in Canada September 25, 1924.

This invention relates to improvements in display boxes and cartons, particularly to boxes made of cardboard and capable of both containing the merchandise and displaying 5 the same, together with suitable advertising matter, when the box is open.

I attain these objects by the method illustrated in the accompanying drawings, in which,

10 Fig. 1 is a drawing of a box in perspective, showing the cover in position as an ordinary cover for the box.

15 Fig. 2 is a drawing of a box in perspective showing the cover folded back for display, exhibiting the contents of the package, and the cover as a display card advertising the goods.

20 Fig. 3 is a drawing of the cover of the box in perspective showing it folded so as to form a show-card with an easel back for display separate from the box.

25 Fig. 4 is a drawing of the cover of the box, 1—1 and 10—10 indicate lines scored on the cover to permit folding, 2 indicates the line of cut permitting design being exhibited for ornamental or advertising display.

30 In the drawings like characters of reference indicate corresponding parts in all the figures.

The device comprises a body 3 in the form of an open top box with flaps 4—4 and a separate closure, having two holding members 5 and 6 folded at 1 and adapted to form 35 a closure for the body by inserting the holding members 5 and 6 between the ends of the box 7 and 8 and contents thereof, to hold the closure in position.

The said closure, is formed intermediate 40 of its length with a line of fold or hinge 10 and the design in part cut out 2, and adapted to be projected upwardly to form a display when the cover is bent backwardly and folded at fold 10 with the holding member 6, also engaging at the end of the box 7 with holding member 5, the portion of the design cut out and the balance of the said closure assuming a substantially vertical position.

50 The holding members 5 and 6 are cut with slots 11 and tongue 12, so that when the cover is removed from the box and folded at hinge 10, the tongue 12 will engage with the slots 11 and together with that portion 55 of the cover folded back form a support that will hold the design substantially in an up-

right position, making the cover useful for display purposes separate from the box.

Boxes constructed of other material such as wood or sheet metal, may be provided 60 with a definite hinge structure at 1 and 10 connecting the two separate parts. Cardboard boxes or cartons may have the cover formed in two separate parts connected by a hinged member of paper, fabric, or the 65 like, attached by glue or suitable means to the two parts. Detail construction in this particular are in one sense immaterial.

I am aware that in previously proposed boxes or cartons, the lid or cover has been 70 creased intermediately of its length and has been provided with a cut-out portion so that the lid or cover can be folded back upon itself to display printed or like matter thereon and has been provided with a front 75 flap or member adapted to engage with the front wall of the box when the lid or cover is in the closed position and capable of being inserted between the rear wall and the contents of the box to hold it in a substantially 80 vertical position. I therefore do not claim such a combination broadly; but—

Having now particularly described and ascertained the nature of my said invention and in what manner the same is to be 85 performed, I declare that what I claim is:—

1. A display carton or box comprising a body portion and a separate removable cover having two holding members therefor, engageable with the ends of the body, said 90 cover being formed intermediate of its length with a line of fold or hinge and a design in part cut out and adapted to be projected upwardly to form a display element when the cover is bent backwardly and folded 95 at the fold or hinge with the two holding members engaging at the same end of the body.

2. A display carton or box according to claim No. 1, comprising a box-like body open 100 at the top and a removable closure for said body, comprising holding member portions at each end normally engaged between the ends of the package and the contents, and a cover portion integral with the upper edge 105 of said holding member portions and forming the closure of the box, said cover being available as a display card in rear of the body by transfer of the holding members from the front to the back of the body, by 110 folding at the fold or hinge and inserting the holding members between the package

and contents at the rear of the body, the portion of the design cut out, and the balance of the cover normally assuming a substantially vertical position.

5. A display carton or box having a separate removable cover according to claim No. 1, in which the holding members of the cover are cut with a slot or slots and tongue, which, when the cover is removed from the package

and folded at the hinge, the tongue will engage with the slot or slots, and together with that portion of the cover folded back form a support that will hold the design substantially in an upright position, making the cover useful for display purposes separate from the box.
